DESIGN FOR A VELOCIPEDe FRAME MEMBER

William I. Smith, Perrysburg, Ohio, assignor to
The Hettrick Manufacturing Company, Toledo,
Ohio, a corporation of Ohio

Application August 5, 1944, Serial No. 114,745

Term of patent 7 years

(Cl. D34—15)

To all whom it may concern:

Be it known that I, William I. Smith, a citizen of the United States and a resident of Perrysburg, Wood County, Ohio, have invented a new, original, and ornamental design for a Velocipede Frame Member, of which the following is a specification, reference being had to the accompanying drawing, forming a part thereof.

In the drawing:

Figure 1 is a front perspective view of the velocipede frame member showing my new design;
Figure 2 is a top plan view; and
Figure 3 is an end elevational view thereof.

I claim:

The ornamental design for a velocipede frame member, as shown.

WILLIAM I. SMITH.
